PERPETUAL CALENDAR

Orpha A. Chidester, San Diego, Calif.

Application May 6, 1933, Serial No. 669,720

8 Claims. (Cl. 40—115)

My invention relates to perpetual calendars, and the objects of my invention are:

First, to provide a perpetual calendar wherein the arrangement of days in any given month of any given year may be readily and quickly selected;

Second, to provide a perpetual calendar wherein the year date is divided so that the calendar may be suitable for dates ranging through several centuries while reducing to a minimum the number of characters needed;

Third, to provide a perpetual calendar in which the entire monthly calendar is exposed to view automatically when the desired year and month are located;

Fourth, to provide a perpetual calendar which requires only a small amount of manipulation in order to be set for use; and

Fifth, to provide on the whole a novelly constructed perpetual calendar which is simple of construction, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application, in which:

Figure 1 is a front view of my perpetual calendar; Fig. 2 is a transverse sectional view thereof through 2—2 of Fig. 1; Fig. 3 is an enlarged sectional view through 3—3 of Fig. 2 showing the front sides of the indicia bearing members.

Similar characters of reference refer to similar parts and portions throughout the several views of the drawing.

Rear indicia member 1, forward indicia member 2, inner mask 3, outer mask 4, journal member 5, and tension washers 6 constitute the principal parts and portions of my novel perpetual calendar.

The perpetual calendar comprises a plurality of disk members mounted in superposed relation. The bottom or rear disk forms a rear indicia member 1. This member includes an arcuate portion 1a upon which are marked a plurality of radiating lines 1b. The lines are intersected by two arcuate rows of characters indicating the various months of the year. The several monthly characters are arranged in groups so as to co-act with other indicia means described hereinafter. The months of January and February are represented

twice, one representation being in the color red to designate their use for leap year only.

The above mentioned arcuate portion 1a normally occupies the upper side of the member 1. A second arcuate portion 1c is formed at the lower portion of the member 1, and is likewise provided with a plurality of radiating lines 1d. The radiating lines 1d form columns which are intersected by arcuately formed lines 1e forming a plurality of rows. Printed in the several squares formed by lines 1d and 1e are a plurality of numerals designating the years in a century, the numerals representing the last two figures in the year dates. The numerals indicating leap year are preferably colored red or the back-ground is so colored.

At one side of the arcuate portion 1c the member 1 is provided with a short extending portion 1f which forms a handle.

Positioned in concentric relation upon the rear indicia member 1 is a forward indicia member 2 which is generally circular in form and is marked with a plurality of radiating lines continuing through an arc somewhat greater than a half circle. The radiating lines are intersected by a plurality of helically positioned lines 2b. The helical lines are so arranged that a new row is begun with every seventh radiating column. Printed or otherwise formed in the several rows are numerals designating the number of days in a month. Each full row contains thirty-one (31) numerals arranged in consecutive order. With this arrangement the exposing of any seventh column brings to view a complete possible calendar month having thirty-one (31) days.

Also printed on the forward indicia member 2 are several numerals designating the first two numbers of the year dates of several centuries. Opposite the year date numerals the indicia member 2 is extended forming a handle portion 2c. An inner mask 3 is positioned over the forward indicia member 2. The mask 3 comprises a major diametered portion 3a occupying approximately a half circle, and a minor diametered portion 3b occupying the remainder of the circle. The major diametered portion 3a is adapted to cover the month characters on the indicia member 1 while both portions of the disk cover the day indicating numerals on the disk 2. The major diametered portion 3a is provided with a slot 3c therein adapted to expose one month character as shown in Fig. 1. Below the slot 3c there is provided a second slot 3d adapted to expose seven columns of the day indicia of the disk 2. Above each of the columns the disk 3 is provided with the conventional week day designating character.

It should be noted that the angular relation of the adjacent lines 2a is the same as the angular relation between adjacent lines 1b so that movement of the disk 3 over one unit of the several 5 columns formed by the line 1b move the disk over one column of the lines 2a.

Positioned on the inner mask 3 is an outer mask 4 which comprises a minor diametered portion 4a of slightly less than a half circle in extent, and 10 a minor diametered portion 4b extending the remainder of the circle. The minor diametered portion 4b is of sufficiently small radius to completely uncover the slot in the mask 3. The major diametered portion 4a is provided with a radially extending slot 4c intersecting its periphery which is adapted to expose a column formed by adjacent pairs of lines 1d. The mask 4 is also provided with a small slot 4d in its periphery adapted to expose any one of the century 15 numerals provided on the indicia disk 2.

The several disks are apertured at the center and receive a journal rivet 5 over the extremities of which are fitted tension washers 6, shown in Figs. 1 and 2.

25 Operation of my perpetual calendar is as follows: The outer mask 4 is shifted relative to the forward indicia member 2 until the desired century indicating numerals are exposed, then the mask 4 and forward indicia member 2 are moved 30 in unison until the desired year date is completed by exposing the proper last two numerals of the year date through the slot 4c. With the mask 4 and indicia members 1 and 2 retained in this position, the mask 3 is shifted arcuately until the 35 desired month is exposed in the slot 3c. When this is done the corresponding calendar arrangement will be exposed in the slot 3d.

As for example, if it is desired to expose the 40 calendar month of April 1933, the slot 4d is positioned so as to expose the numeral 19 on the indicia member 2, the slot 4c is positioned so as to expose the numerals 33 on the indicia member 1, and the slot 3c is shifted until the word April 45 is exposed therein. By changing the number of the century date exposed, the calendar may be used to determine any date in the future or in the past since September 14, 1752, when the first Gregorian calendar was adopted.

It should be here noted that each column of 50 year dates on the member 1 indicate normal years wherein the twelve months thereof begin on identical days; thus the two members 1 and 2 are set in the same relation to be operable for the years 1911, 1922, and 1933, etc. Also for any adjusted 55 relation of the members 1 and 2 wherein the year dates register with the notches 4c and 4d, a complete composite year calendar is formed by the month characters and their respective groups of numerals.

60 Though I have shown and described a particular construction, combination, and arrangement of parts and portions, I do not wish to be limited to this particular construction, combination, and arrangement, but desire to include in the scope 65 of my invention the construction, combination, and arrangement substantially as set forth in the appended claims.

Having thus described my invention, what I 70 claim as new and desire to secure by Letters Patent is:

1. A perpetual calendar comprising, a plurality of disks arranged in superposed relation adapted to be shifted relatively to each other about a common axis, century representing characters on 75 one disk, numerals on another disk representing

the different years of a century, and means on a third disk for designating particular century representing characters and year representing numerals to mark a completed year date.

2. A perpetual calendar comprising, a plurality 5 of disks arranged in superposed relation adapted to be shifted about a common axis, century representing characters on one disk, numerals on another disk representing the different years of a century, means on a third disk for designating 10 particular century representing characters and year representing numerals to mark a completed year date, a plurality of numerals representing the several possible month calendars, a plurality of characters representing the possible months 15 in a year, said numerals and characters arranged on the two first mentioned disks in coactive relation, and means for designating a particular month and a corresponding month calendar.

3. A perpetual calendar comprising, a pair of 20 relatively shiftable members the one bearing century dates, the other bearing the yearly divisions of a century, means for designating a century date and a yearly division thereof to indicate a complete year date, one of said shiftable members 25 bearing characters representing the several months of a year, the other bearing indicia representing the several possible monthly calendars, said indicia and characters adapted to be disposed in corresponding relation upon adjustment of said shiftable members to indicate a given year date, and an instrumentality for designating a particular month character and its corresponding month calendar indicia.

4. A perpetual calendar comprising, a first 35 member, characters thereon representing the several months of a year, a second member, a series of overlapping groups of indicia thereon, each group representing a possible month calendar, one of said members bearing a plurality of 40 year dates arranged in groups, the normal years represented in each group having identical arrangements of month calendars for corresponding months thereof, slotted mask means associated with the other member for designating 45 any one of the several groups of year dates whereby the month characters and month calendar groups are in predetermined corresponding relation, and an instrumentality for designating a particular month character and its corresponding 50 month calendar group.

5. A perpetual calendar comprising, a first indicia bearing member, having helical rows of numerals thereon arranged in overlapping relation forming a plurality of radiating columns of 55 numerals, successive groups of columns forming month calendars, a second indicia bearing member having characters representing the months of a year, slotted mask means for designating particular month characters and month calendars, said members being relatively shiftable whereby the various possible month calendars for a given month register with said means, and means including year date indicia for setting said members whereby the month characters 65 and month calendars are disposed in the correspondence obtaining during a given year.

6. In a perpetual calendar, a chart having year dates arranged in groups in which all the normal years having identical arrangements of month 70 calendars for corresponding months are arranged in a single group, means for designating each of said groups, and a composite year calendar including relatively shiftable month indicia and month calendars adapted to be set to represent 75

each of the various possible month calendar arrangements, said composite year calendar also including supplementary month calendar units and month representing characters relating to 5 the months varied in arrangement by reason of leap year.

7. In a perpetual calendar, a chart having year dates arranged in groups in which all the normal years having identical arrangements of month 10 calendars for corresponding months are arranged in a single group, means for designating each of said groups, a composite year calendar including relatively shiftable month indicia and month 15 calendars adapted to be set to represent each of the various possible month calendar arrangements, and an instrumentality for designating a particular month and corresponding month calendar of said composite year calendar, said composite year calendar also including supplementary month calendar units and month rep- 20

resenting characters relating to the months varied in arrangement by reason of leap year.

8. A perpetual calendar comprising, a first member, characters thereon representing the several months of a year, a second member, a 5 series of overlapping groups of indicia thereon, each group representing a possible month calendar, one of said members bearing a plurality of year dates arranged in groups all the years of similar classification as to arrangements of month 10 calendars for corresponding months thereof being placed in a single group, means associated with the other member for designating any one of the several groups of year dates whereby the month characters and month calendar groups 15 are in predetermined corresponding relation, and an instrumentality for designating a particular month character and its corresponding month calendar.
